 Original application Nov. 10, 1964, Ser. No. 410,177, now Patent No. 3,320,432, dated May 16, 1967. Divided and this application Mar. 23, 1967, Ser. No. 646,774
 5 5 Claims. (Cl. 307—88.3)

ABSTRACT OF THE DISCLOSURE

A low noise parametric amplification system having a parametric down-converter for converting input signals of frequency f_2 to a lower frequency f_1 . The down-converter is coupled to a parametric upper-sideband up-converter which converts signals of frequency f_1 to a higher frequency f_3 . The up-converter is coupled to the utilization load either directly or through a circulator. The noise signals that are generated by the load are prevented from being coupled to the down-converter, where they would be amplified, by either the circulator or the up-converter. Alternative arrangements are also covered.

This application is a division of application Ser. No. 410,177, filed Nov. 10, 1964 now U.S. Patent No. 3,320,432 and entitled, "Parametric Amplification Systems Utilizing Low Pump Frequencies."

This invention relates to low noise parametric amplification systems and, more particularly, to such systems utilizing pump frequencies substantially lower than twice the input signal frequency.

Conventional parametric amplifier systems have generally required pump frequencies at least twice as great as the frequency of input signals which are to be amplified. That type of operation is acceptable for a large range of applications, however, there is a growing field of applications where it is either desirable or necessary to provide operation with pump frequencies as low as possible. For example, in the rapidly expanding area of millimeter wave applications it is difficult and uneconomical to provide pump frequencies in the high frequency portion of the millimeter range. Thus, if an input signal has a frequency of 40 gigacycles, a degenerate type of parametric amplifier would require a pump frequency twice as great as the input signal frequency, or a pump frequency of 80 gigacycles. It is difficult and costly to provide a pump power at a frequency of 80 gigacycles and it is therefore desirable to provide arrangements allowing operation with lower pump frequency.

It is known that parametric down-converter can be used to convert high frequency input signals to signals of lower frequency, so that these signals of lower frequency can then be amplified using conventional arrangements with reasonable pump frequencies. By using a regenerative down-converter both amplification and conversion to lower frequency can be accomplished in the conversion process. The principal problem involved in using either a regenerative or a nonregenerative down-converter for this purpose is that increased noise may be introduced so as to degrade the final signal-to-noise ratio, thereby making extremely low noise operation impossible.

The objects of this invention are, therefore, to provide parametric amplification systems which avoid disadvantages of prior art systems and which achieve low noise operation with pump frequencies substantially lower than twice the frequency of the input signals.

For a better understanding of the present invention together with other and further objects thereof, reference is had to the following description taken in connection

with the accompanying drawings, and its scope will be pointed out in the appended claims.

In the drawings, FIGS. 1, 2, and 3 show different types of low noise parametric amplification systems constructed in accordance with the invention.

Referring now to FIG. 1 there is shown a portion of a parametric amplification system of the type wherein an input signal is processed prior to coupling to a signal-utilization load. This system includes the improvement, for providing low noise operation with a pump frequency substantially lower than twice the input signal frequency, comprising the combination of the following. Parametric down-converter means, shown as regenerative down-converter 10, for converting input signals of frequency f_2 to signals of a lower frequency f_1 . Parametric upper-sideband up-converter means, shown as up-converter 12, for converting signals of frequency f_1 to signals of a higher frequency f_3 . Means intercoupling the down-converter 10 and the up-converter 12. These last means are shown as nonreciprocal coupling means in the form of circulator 14 and interconnecting transmission lines. As shown, circulator 14 is interconnected so that it acts to couple processed input signals from down-converter 10 to the input port of the signal utilization load 16, while at the same time any noise coupled back from the input port of load 16 is coupled to up-converter 12. In this way noise from the load 16 is prevented from being coupled to the down-converter 10, where it would be reflected with amplification and coupled back to the load 16. As shown, there is also included dissipation means, shown as resistor 18, for resistively dissipating signals up converted by up-converter 12.

Considering now the operation of the FIG. 1 arrangement, for purposes of example FIG. 1 may be considered to show a portion of a radar system wherein radar echo signals intercepted by an antenna are coupled to terminals 20 for processing prior to being coupled to signal utilization load 16 for further processing and derivation of radar information. The arrangement shown provides low noise parametric operation in such a system with a pump frequency substantially lower than twice the signal input frequency. Down-converter 10 operates with a pump frequency f_{p1} to convert input signals of frequency f_2 to signals of a lower frequency f_1 where the interrelation of these frequencies is such that $f_{p1}=f_2+f_1$. If desired, down-converter 10 can also amplify the input signal.

The signals of frequency f_1 are then coupled, via the circulator 14, to signal utilization load 16. Signal utilization load 16 may take any one of a variety of forms, such as a detector circuit, a vacuum tube amplifier, etc. As is well known, a common attribute of all such loads is an input port which acts as a noise source. If circulator 14 were removed from the circuit and down-converter 10 coupled directly to load 16, noise from the input port of load 16 would be coupled back to the down-converter 10. As is known, down-converter such as 10, act as a negative resistance with respect to signals coupled into the output port. Noise signals coupled back from the input port of load 16 would therefore be reflected with amplification by the down-converter 10. These amplified noise signals would then be coupled to load 16 and would act to degrade the signals of frequency f_1 which are coupled to the load 16 for final utilization. In accordance with the invention, the circulator 14 acts to couple the noise signals originating at the input port of load 16 to up-converter 12. In upper-sideband up-converter 12, these noise signals are converted to a higher frequency f_3 and then dissipated in resistor 18. Up-converter 12 operates with a pump frequency f_{p2} and the interrelation of the frequencies involved is such that $f_3=f_{p2}+f_1$. As described in greater detail in applicant's application entitled "Low Noise Termination" Ser. No. 33,990, filed June 6, 1960,

now Patent No. 3,181,078, this process of up-conversion and termination results in only a small amount of noise being available at the input port of up-converter 12 for coupling back to the down-converter 10 (via circulator 14). Since, in accordance with the invention, only a small amount of noise is coupled back to the down-converter 10, no serious degradation of the signals of the frequency f_1 coupled to load 16 will result. Thus, the invention makes possible low noise amplification without the requirement for pump signals of frequencies in the range of twice the input signal frequency. The frequencies of the two pump signals required are related to the input signal by the equations given above, and the required pump signal frequencies are substantially lower than twice the input signal frequency f_2 .

It will now be appreciated that known types of parametric up-converters and down-converters, circulators, etc., can be utilized and the present invention lies in the novel combination of such elements as described. A further simplification is possible by using a single pump source to supply pump signals for down-converter 10 and up-converter 12. That is to say, frequency f_{p1} may be the same frequency as frequency f_{p2} if desired.

Referring now to FIG. 2, there is shown a second arrangement in accordance with the invention. In the FIG. 2, down-converter 10, up-converter 12 and signal utilization load 16 are as described with reference to FIG. 1 and the frequencies involved are related by the same equations: $f_{p1}=f_2+f_1$ and $f_3=f_{p2}+f_1$.

The FIG. 2 system preferably uses a regenerative down-converter 10 followed by upper-sideband up-converter 12. Up-converter 12 acts as a low noise post amplifier for the down-converter 10. The up-converter 12 followed by load 16 provides low noise signal conversion and also acts as a low noise termination for the down-converter 10, so that the down-converter 10, acting as a negative resistance one-port amplifier, does not reflect much noise back to the signal utilization load 16. The complete system of FIG. 2 provides low noise amplification and is useful with pump frequencies close to the input signal frequency.

Referring now to FIG. 3 there is shown another arrangement in accordance with the invention. The FIG. 3 system is similar to the FIG. 2 system except that a circulator 14 has been inserted between up-converter 12 and load 16. In operation of the FIG. 3 system, noise coupled back from the input port of load 16 is coupled to resistor 22, via circulator 14, where it is dissipated. The addition of the circulator 14 provides the important advantage of isolation so that any variations in the characteristics of load 16 are prevented from affecting the operation of both up-converter 12 and, especially, down-converter 10.

Of special interest is the result obtained by pumping both the down-converter 10 and the up-converter 12 of FIGS. 2 and 3 from a single pump source. Such an arrangement results in an amplifier which has improved stability under conditions of varying pump signal power. If the diodes of converters 10 and 12 are pumped approximately equally hard, they will both have the same variation in the first harmonic elastance factor and as a result, the reflection coefficient will be stabilized to some extent. Also, if the pump frequencies of the down-converter 10 and the up-converter 12 are chosen to be equal, the same diode can be used by both the down-converter 10 and the up-converter 12. However, the same diode can only be used in the embodiments shown by FIGS. 2 and 3 where there are no elements between the down-converter 10 and the up-converter 12.

Approximate noise figures for certain of the above-discussed arrangements will now be derived. The assumption will be made that the principal loss involved is in the termination of the f_3 signals and other losses will be ignored. Assume that down-converter 10 presents a reflection coefficient magnitude of $|\rho|^2$ at its f_1 output. All

powers will be normalized to the available power of the f_2 signal source (the incident power) in this discussion.

The f_2 power entering the down-converter 10 is $(1-|\rho|^2)$, $|\rho|^2$ will be assumed to be greater than 1. Therefore, the power flow is outward at frequency f_2 . The Manley-Rowe relations lead to the result that the power leaving down-converter 10 at frequency f_1 is

$$\frac{f_1}{f_2} (|\rho|^2 - 1)$$

10 The Manley-Rowe relations require that power flow into up-converter 12 at one port and flow out at the other port. Thus, the power dissipated in the f_3 termination is:

$$\frac{f_3}{f_1 f_2} (|\rho|^2 - 1) = \frac{f_3}{f_2} (|\rho|^2 - 1) \quad (1)$$

15 Equation 1 gives the gain of the FIG. 2 system and also the FIG. 3 system.

System noise comes almost solely from the termination of the f_3 signals. In FIG. 2, the f_3 signal termination is the signal utilization load 16 which would be likely to be a mixer. The correlation between load output noise and noise available from the load input port is not known, however the analysis can be made more definite by considering the FIG. 3 circuit rather than the FIG. 2 circuit.

20 The f_3 signal termination is assumed to be at temperature T_0 , which is the temperature of the source of the f_2 frequency input signals. Actually, the f_3 signal termination would be at ambient temperature, but the simplest case is taken for purposes of explanation. In a lossless converter the reflection coefficient magnitude is the same at either end. Likewise, the reflection coefficient magnitude at either end of the two cascaded converters 10 and 12 is the same in the ideal case. (The converters 10 and 12 are cascaded in FIGS. 2 and 3 but not in FIG. 1.)

25 Considering the circuit of FIG. 3, the noise kT_0B from the f_3 termination 22 is reflected from the output terminal of the up-converter 12 and $|\rho|^2 kT_0B$ reaches the load 16. The noise figure of this converter system is:

$$40 F = 1 + \frac{|\rho|^2}{\frac{f_3}{f_2} (|\rho|^2 - 1)} \quad (2)$$

The general equation for noise measure is:

$$45 M = \frac{F-1}{1 - \frac{1}{G}}$$

where G is the gain. Therefore the noise measure of this system is:

$$50 M = \frac{|\rho|^2}{\frac{f_3}{f_2} (|\rho|^2 - 1) \left(1 - \frac{1}{\frac{f_3}{f_2} (|\rho|^2 - 1)} \right)} = \frac{|\rho|^2}{\frac{f_3}{f_2} (|\rho|^2 - 1) - 1} \quad (3)$$

55 The noise measure is:

$$M = \frac{F-1}{1 - \frac{1}{|\rho|^2}} = \frac{f_2}{f_3} \quad (4)$$

60 For the FIG. 1 system, the noise factor is:

$$F = 1 + \frac{\frac{|\rho|^2 f_1}{f_3}}{\frac{f_1}{f_2} (|\rho|^2 - 1)} \quad (5)$$

65 Therefore the noise measure is:

$$70 M = \frac{\frac{f_1}{f_3} |\rho|^2}{\frac{f_1}{f_2} (|\rho|^2 - 1) \left(1 - \frac{1}{\frac{f_1}{f_2} (|\rho|^2 - 1)} \right)} \quad (6)$$

$$M = \frac{|\rho|^2}{\frac{f_3}{f_2} (|\rho|^2 - 1) - \frac{f_3}{f_1}} \quad (7)$$

For very high frequencies (i.e., f_2 equals 3kMc or higher) the FIG. 1 system requires good signal utilization load 16 noise figures unless large regeneration in down-converter 10 is provided. In a practical system it is preferable to operate with small regeneration (small $|\rho|$) so that circuit adjustment is not critical. With the arrangements of FIGS. 1 and 3, the converter noise figure (the values of F as calculated here) goes to infinity as $|\rho|$ approaches unity. In FIG. 2, the correlation between directly transmitted and reflected load noise might allow some improvement by choosing proper line lengths between the load and the up-converter 12.

While there have been described what are at present considered to be the preferred embodiments of this invention, it will be obvious to those skilled in the art that various changes and modifications may be made therein without departing from the invention and it is, therefore, aimed to cover all such changes and modifications as fall within the true spirit and scope of the invention.

What is claimed is:

1. A low noise parametric amplification system, for processing input signals prior to final utilization, comprising:

first apparatus including regenerative parametric down-converter means, operating with a pump frequency f_{p1} , for converting input signals of frequency f_2 to signals of a lower frequency f_1 , where $f_{p1}=f_2+f_1$ and parametric upper-sideband up-converter means, directly connected to said down-converter means and operating with a pump frequency f_{p2} , for converting signals of frequency f_1 to signals of the higher frequency f_3 , where $f_3=f_{p2}+f_1$; a signal utilization load having an input port which couples back noise; and means coupling said first apparatus to said load; whereby said up-converter means prevents noise signals from being coupled back from said input port of said load to said down-converter means, and said up-converter provides a low noise termination for said down-converter means.

2. A low noise parametric amplification system, for processing input signals prior to final utilization, comprising:

regenerative parametric down-converter means, operating with a pump frequency f_{p1} , for converting input signals of frequency f_2 to signals of a lower frequency f_1 , where $f_{p1}=f_2+f_1$; parametric upper-sideband up-converter means, directly connected to said down-converter means and operating with a pump frequency f_{p2} , for converting signals of frequency f_1 to signals of a higher frequency f_3 , where $f_3=f_{p2}+f_1$; a signal utilization load having an input port which couples back noise; and means coupling said down-converter means to said up-converter means and said up-converter means to said load; whereby said up-converter means prevents noise signals from being coupled back from said input port of said load to said down-converter means, and said

up-converter provides a low noise termination for said down-converter means.

3. A low noise parametric amplification system, for processing input signals prior to final utilization, comprising:

first apparatus including regenerative parametric down-converter means, operating with a pump frequency f_{p1} , for converting input signals of frequency f_2 to signals of a lower frequency f_1 , where $f_{p1}=f_2+f_1$ and parametric upper-sideband up-converter means directly connected to said down-converter means and operating with a pump frequency f_{p2} , for converting signals of frequency f_1 to signals of a higher frequency f_3 , where $f_3=f_{p2}+f_1$;

a signal utilization load having an input port which couples back noise;

means for resistively dissipating said noise near the frequency f_3 without further utilization;

and nonreciprocal coupling means having a first port connected to said first apparatus, a second port connected to said load and a third port connected to said dissipation means, for coupling f_3 signals from said up-converter means to said load and for coupling noise signals from said load to said dissipation means.

4. A low noise parametric amplification system, for processing input signals prior to final utilization, comprising:

regenerative parametric down-converter means, operating with a pump frequency f_{p1} , for converting input signals of frequency f_2 to signals of a lower frequency f_1 , where $f_{p1}=f_2+f_1$;

parametric upper-sideband up-converter means, directly connected to said down-converter means and operating with a pump frequency f_{p2} , for converting signals of frequency f_1 to signals of a higher frequency f_3 , where $f_3=f_{p2}+f_1$;

a signal utilization load having an input port which couples back noise;

means for resistively dissipating said noise near the frequency f_3 without further utilization on;

and nonreciprocal coupling means, having a first port connected to said up-converter means, a second port connected to said load and a third port connected to said dissipation means, for coupling f_3 signals from said up-converter means to said load and for coupling noise signals from said load to said dissipation means.

5. A system in accordance with claim 4, wherein pump frequency f_{p1} is the same frequency as the pump frequency f_{p2} .
